UNITED STATES PATENT OFFICE.

AKOS MAJERNIK AND CHARLES MAJERNIK, OF KNOXVILLE, TENNESSEE.

IGNITION TIMER FOR INTERNAL-COMBUSTION ENGINES.

Application filed January 25, 1923. Serial No. 614,792.

This invention relates generally to internal combustion engines, having more particular reference to an internal combustion engine intended more particularly for use on motorcycles and having a number of cylinders arranged at an angle to one another around a common centre.

For further comprehension of the invention, and of the objects and advantages there-
10 of, reference will be had to the following de-
scription and accompanying drawings, and
to the appended claims in which the various
novel features of the invention are more par-
ticularly set forth.

15 Fig. 1 of the drawings is an axial vertical
sectional view of a motorcycle engine with
our timer applied thereto.

Fig. 2 is a detail face view of the ignition
timer.

20 Fig. 3 is a transverse vertical section on
the line 3—3 of Fig. 2.

The spark timing device is shown in detail
in Figs. 2 and 3 and comprises a cylindrical
offset 55 from the casing element 42 coaxial
25 to one of the cam shafts 44. Rotatable in
this offset is a thick metal ring 56 formed
with an annular groove in its outer end face
to receive an insulating ring 57. This latter
ring has three bosses 58 on its inner wall
30 which project through openings in the inner
wall of the groove in ring 56 and are flush
with the inner faces of the latter. Set into
these bosses are screws 59 having binding
nuts 60 on their projecting outer ends to re-
ceive the lead wires. The return is ground-
35 ed to the engine, a flat spring 62 being fixed

at one end to the cam shaft 44 and having
fixed to its opposite end a block 63 carrying
a ball 64 which is pressed outwardly against
the ring 56 by said spring. The block 63 is 40
radially slidable in a recess 65 formed in a
collar 66 fixed to the cam shaft. To vary
the timing the ring may be given a rotary
movement by an arm 67 fixed thereto and
connected with an operating handle, not 45
shown.

Having thus described our invention what
we claim as new and desire to protect by
Letters Patent of the United States is as
follows:

1. In an internal combustion engine, tim-
ing means comprising a rotary shaft, a shift-
able ring surrounding said shaft, a series of
contacts carried by said ring, a flat spring
fixed at one end to said shaft, a recessed col-
lar on said shaft, a block radially slidable in
the recess of said collar, and a ball carried
by said block and pressed outwardly against
said ring by said spring. 50

2. In an internal combustion engine, tim-
ing means comprising a rotary shaft, a shift-
able ring surrounding said shaft, a series of
contacts carried by said ring, a flat spring
fixed at one end to said shaft, a block mount-
ed on the opposite end of said spring, and a
ball seated in a recess in said block and press-
ing against said ring. 60

In testimony whereof we have affixed our
signatures.

AKOS MAJERNIK.
CHARLES MAJERNIK.
